[57] ABSTRACT

An electronic musical instrument having mainly digital circuits for producing sounds in correct musical scales as well as for producing variegated sounds and designed in this manner it may be easy to play the notes of the scales on the instrument.

ELECTRONIC MUSICAL INSTRUMENT HAVING
KEYBOARDS

BACKGROUND OF THE INVENTION

Average pulse periods of the pulse trains change by preventing the passage of a pulse of the output pulse trains supplied from a pulse generator. The ratio of the average pulse periods is determined by the key which is touched. The pulses flow into a counter wherein the counter always returns to its reset condition after certain total input pulses are supplied. Consequently, the actuations of the counter per cycle are proportional to the average pulse periods. The electric waveforms produced in the process of the actuations of the counter are amplified and then converted into musical sounds.

The electronic musical instrument constructed and arranged in the manner described above make it convenient to produce the sounds of the musical scales of pure temperament.

It is possible to play the electronic musical instrument according to the invention in such a manner that touching a key of the keyboard produces the corresponding sound having the same syllable name irrespective of any keys or tones by means of modulating the average pulse periods of the output pulses produced from a pulse generator.

It is also possible to obtain a variety of waveforms and of modulations in periodic vibrations of counters by using digital circuits herein described in detail.

The present invention is concerned generally with an electronic musical instrument having keyboards and, more particularly, the invention relates to an electronic musical instrument having circuits in which the waveforms of arbitrary sounds can be produced electronically.

The highness or lowness of a sound is determined by the frequencies thus the pitch is dependent on its rate of vibration.

In music there are two kinds of pitch notations: absolute pitch, which is the position of a musical tone considered in reference to the whole range of pitch or to a standard scale and determined by its rate of vibration; and relative pitch, of which musical tone is determined by its relative position in a scale.

Table 1 shows the syllable names and their corresponding ratios of periodic vibrations in which both major and minor keys of pure temperament have the same key-note. Do-sharp is positioned between notes do and re, fa-sharp between fa and sol.

Table 1

Interval	Syllable Names	Ratios of periodic vibrations on the basis of key-note as 1	Ratios of periodic vibrations on the basis of note sol as 1
Unison	Do	1	3/2
Semitone	Do-sharp	15/16	45/32
Major tone	Re	8/9	4/3
Minor third	Mi in minor	5/6	5/4
Major third	Mi in major	4/5	6/5
Perfect fourth	Fa	3/4	9/8
Augmented fourth	Fa-sharp	32/45	16/15
Perfect			

Table 1-Continued

Interval	Syllable Names	Ratios of periodic vibrations on the basis of key-note as 1	Ratios of periodic vibrations on the basis of note sol as 1
Fifth	Sol	2/3	1
Minor sixth	La in minor	5/8	15/16
Major sixth	La in major	3/5	9/10
Minor seventh	Ti in minor	5/9	5/6
Major seventh	Ti in major	8/15	3/10
Octave	Do	1/2	3/4

The key-note in minor keys is the so-called note la, however, in the description of the invention, the key-note in minor keys is described as the note do, and notes re, mi, fa, etc. are followed.

Regarding the notes mi, la and ti, the pitches of major and these of minor keys have different periodic vibrations so that these variations of the vibrations are shown in above-mentioned Table.

The musical scales of pure temperament are arranged in integral numbers of periodic vibrations as seen in Table 1 and the tones and/or sounds arranged in order of the above scales are superior to that produced by common musical keyboard instruments

which are arranged in the scales of equal temperament, with regard to musical chords in harmony as well as to melodies.

SUMMARY OF THE INVENTION

It is, therefore, an object of the present invention to provide an improved electronic musical instrument by which the tones and/or the sounds of the scales of pure temperament can be easily produced.

It is another object of the invention to provide an improved electronic musical instrument in which touching a key of the keyboards produces the corresponding sounds having the same syllable name irrespective of any keys or tones.

It is still another object of the invention to provide an improved electronic musical instrument by which harmonized chords as well as the chords that are not shown in Table 1 can be obtained.

It is yet a further object of the present invention to provide an improved electronic musical instrument by which correct frequencies of an arbitrary sound can be easily obtained in any keys or tones.

It is further and another object of the invention to provide an improved electronic musical instrument by which continuous sounds having arbitrary waveforms can be produced.

It is further and another object of the invention to provide an improved electronic musical instrument by which rising sounds as well as falling sounds can be freely obtained.

It is further and another object of the invention to provide an improved electronic musical instrument by which variations in the pitch of the sounds such as vibrato and portamento can be arbitrarily and correctly obtained.

It is further and another object of the invention to provide an improved electronic musical instrument

having the circuits which have advantages of being simple and economical.

Other objects, features and advantages of the electronic musical instrument according to the present invention will become apparent from the following detailed description of the invention taken in conjunction with the accompanying drawings in which like reference numerals and characters designate corresponding parts and elements throughout the figures and in which:

BRIEF DESCRIPTION OF THE DRAWINGS

FIG. 1 shows logic symbols and the truth tables of digital circuits which employ binary numbers in digital form.

FIG. 2(a) is a schematic circuit diagram showing a preferred form of the circuit having a conventional binary counter in which flip flops are connected together in cascade. FIGS. 2(b) and (c) are block diagrams of FIG. 2(a).

FIG. 3(a) is a schematic circuit diagram showing a preferred form of the reversible binary counter having exclusive OR circuits and, FIG. 3(b) and (c) are block diagrams of FIG. 3(a) respectively.

FIG. 4(a) is a schematic circuit diagram having a digital comparator. FIG. 4(b) is a block diagram of FIG. 4(a).

FIG. 5(a) is a schematic circuit diagram in which at least one pulse of some pulses is prevented to pass. FIG. 5(b) is a block diagram of FIG. 5(a) and FIG. 5(c) is that of the inner part of the shown dotted lines of FIG. 5(b).

FIG. 6 is a block diagram having two parts of MOs shown in FIG. 5(a). The output of the MI is so arranged to connect the input of two MOs in a parallel.

FIG. 7 is a principle circuit diagram showing an overall electronic arrangement of the musical instrument according to the present invention.

FIG. 8 is a block diagram showing a preferred form of the connections of the switches connected with both to the keys of keyboards shown in FIG. 7 and to the circuit.

FIG. 9 is a circuit having a pulse generator G-0 of which frequencies are settled are not to be modulated. Average pulse periods provided to a circuit N-1 are modulated by both the pulse generator G-0 and a circuit N-4.

FIG. 9a is a schematic circuit diagram showing another preferred form of a circuit in which pulse trains for making harmonic musical scales of pure temperament can be produced.

FIG. 10 is a circuit in which varieties of waveforms can be made.

FIG. 11 is a schematic circuit diagram showing another preferred form of a circuit in which varieties of waveforms can also be made.

FIG. 12 shows relationship between a characteristic of the input and output of nonlinear circuit and its waveforms.

FIG. 13(a) is a circuit in which decrement waveforms are obtained and, FIG. 13(b) shows its waveform.

FIG. 13c is a schematic circuit diagram showing another preferred form of the circuit in which decrement waveforms are also obtained.

FIG. 14 is a schematic circuit diagram in which a continuous glide effectiveness of sounds such as portamento is produced.

FIG. 15 is a circuit for producing slight and rapid variations in the pitch of the tone such as vibrato.

FIGS. 15(a) and 15(b) are block diagrams having a circuit for producing the sounds and/or tones which have a depth as well as an expression of mixed feelings.

FIG. 16 is a circuit in which a variety of sounds in pitch as well as many numbers of sounds can be produced at the same time.

FIG. 17 is a circuit in which pluralities of harmonized sounds to a melody can be produced.

FIG. 18 is a circuit in which three chords can be produced.

DESCRIPTION OF THE PREFERRED EMBODIMENT

15

Reference is now made to the drawings, first to FIG. 1 illustrating logic symbols and the truth tables of digital circuits which accept binary numbers in digital form and employ some form of a binary number system.

20

Here represented are high level voltage (referred to as H) and low level voltage (referred to as L). The inputs of the AND gate circuit and the OR gate circuit shown respectively in FIGS. 1(a) and 1(b) are not limited to just two inputs. When necessary, a plurality of inputs

25

may be employed. The small circle shown in the logic symbol of the inhibit gate circuit of FIG. 1(d) indicates an inverter. Output voltage of the J-K flip flop shown in FIG. 1(e) are variable when the input voltage to CP changes from a high-voltage condition to a condition.

30

When the input voltage to J or K is always at a high level, these symbols will be omitted in the specification. The output voltage of the flip flop changes to a low-voltage condition at the instant any high level voltage is supplied to a reset terminal R. On the other hand,

35

when the voltage supplied to the reset terminal R is kept at a low level, the symbols of the reset terminal will be omitted.

40

FIG. 2(a) is a schematic circuit diagram showing a preferred form of a circuit having well-known binary counter in which flip flops are connected together in cascade. FIG. 2(b) is a block diagram of FIG. 2(a). The symbol R written in a box of FIG. 2(b) shows that the output voltage of the flip-flops change to a reset condition (the output voltage Q from four flip flops is in a low-condition) at the instant the high level voltage is supplied to the reset terminal R. The number 5, written in the left bottom of the box explains that the counter turns to a reset condition every five pulses when inputs supplied to the terminal are in high-volt conditions.

45

The number 16, written in an upper portion of the box of FIG. 2(b), shows that the outut voltage of the flip-flops turns to a reset condition every sixteen pulses when inputs supplied to the terminal R and to the part where the number 5 is written are at a low level-voltage. The output of the voltage will be written at the right-side of the box of FIG. 2(b). Output lines connected to numbers with a circle, for example, ①, ②, ④, ⑧ are the output Q from the flip flops. FIG. 2(c) is a block diagram showing these output lines.

50

When the output Q of the flip-flop is in a high-voltage condition, the logic state will be designated as 1, and when it is in a low-voltage state, the logic code will be 0. These binary codes of the logics are in order from that of the last flip flop and, are referred to as the indicated numbers of the counter 1. The indicated numbers show the number of pulses which are supplied to the counter after it is reset.

60

When the output Q of the flip-flop is in a high-voltage condition, the logic state will be designated as 1, and when it is in a low-voltage state, the logic code will be 0. These binary codes of the logics are in order from that of the last flip flop and, are referred to as the indicated numbers of the counter 1. The indicated numbers show the number of pulses which are supplied to the counter after it is reset.

On the other hand, the output voltage from the AND circuit A-3 shown in FIG. 2(a) will be at a high level when the indicated number is 3, 7, 11 and 15. These output voltages will be described at the right bottom of the box of FIGS. 2(b) and (c) as the numbers bearing no circle.

The numbers indicated by the counter in FIG. 2 increases every time a total number of input pulses are supplied to it. When a maximum number is reached, the counters are reset to zero. Reversible counters are also well-known in the state of the art. These counters will increase until a maximum number of pulses have been counted and then decrease until a minimum has been reached.

FIG. 3(a) is a schematic circuit diagram showing a preferred form of the reversible counter having Exclusive OR gates E-1 to E-5 in which indicated numbers increase when the output voltage (32) from the flip flop connected subordinately lastly is in the low level. Conversely, the indicated numbers will decrease when the above-mentioned output voltage is at the high level. FIGS. 3(b) and (c) are block diagrams of FIG. 3(a). The required number of input pulses for the counter to return to a reset condition is twice the number shown between the arrows.

FIG. 4 is a schematic circuit diagram of a preferred form of a digital comparator circuit. It is known that output voltage actuated by the digital comparator varies at a high or low level corresponding to binary numbers in digital form. As illustrated in FIG. 4(a), the output voltage from the OR gate circuit OR-2 changes in a low level condition and the flip flop F-5 composed of two AND circuits A-4 and A-5 are reset, and the output voltage from the flip flop changes at a low level. This takes place when the indicated numbers of the counter C-1 are varying rapidly as compared with the indicated numbers of the counter C-2, and then numbers of the last five bits of the counter C-1 are equivalent to the indicated numbers of the counter C-2. The flip flop F-5 is set when the number in counter C-1 is 32. However the flip flop can not be reset while the counter C-1 indicates more than 32. The equation described under the output line of FIG. 4(b) is conditioned upon a high-voltage level output. This equation are be changed according to the variety of digital comparator circuits.

FIG. 5(a) is a schematic circuit diagram having a circuit in which a pulse of the pulse trains is prevented to pass due to the operation of the counters. As illustrated in the drawing, a pulse supplied to the counter is prevented to pass through an AND circuit A-13, for example, an input line I-7 is in a high-volt condition and when the counter C-3 indicates that its numbers are 3, 7, 11 and 15. Thus a pulse train of four pulses is prevented to pass.

When input line I-5 is in a high-volt condition, the output from an OR gate circuit OR-4 turns to be at a high level when the counter indicates that the number is 3 or 11 despite input lines I-2, I-3 and I-4 being in the low-voltage conditions.

The input pulses supplied from an input line I-10 pass through the counter C-3. Consequently, if the output Q from the flip flop F-6 is in a low-volt condition the next pulse is prevented to pass through the AND circuit A-14. However, if the a output Q of a flip flop F-6 is in a high-volt condition, then following sequence of pulses can pass through the AND gate circuit A-14. Thus, a pulse is prevented to pass through the AND circuit A-14 when the next condition of counter C-3 is at a high level.

This also means that a pulse prevented to pass through the AND circuit A-14 can not pass through the counter.

Table 2 shows the actuation of the counter C-3 and the conditions of prevention of the passage of pulses when some of the input lines I-1 to I-9 of FIG. 5(a) are in a high-volt conditions. The fractionary numbers shown in the boxes of FIG. 5(b) are the ratios of the average pulse periods when the input lines I-1 to I-9 are in high-volt conditions. MI, containing the counter C-3, is the section in which the input to a counter is prevented, while right-side box MO is a part in which the input to a counter is not prevented. As shown in FIG. 5(c), a block diagram of the inner portion of the dotted lines of the box of FIG. 5(b), the fractionary numbers are also the ratios of the average pulse periods when the input lines shown below are in high-volt conditions. One MO or more MOs which do not prevent the passage of the input to the counter can be connected to the only one MI.

Table 2

Input lines which are in high-volt conditions	Numbers of pulses from a reset condition of the counter to the next reset condition	Indicated numbers by C-3 when a pulse is pulled out by A-14	Numbers of pulses pulled out by A-14 during one complete cycle	Indicated numbers by C-3 when a pulse is pulled out by A-13	Numbers of pulses pulled out by A-14 during one complete cycle	Ratios of average pulse period
I-9	16				0	1
I-8	16				16/15	
I-5, I-9	16				9/8	
I-5, I-9	5	4, 12	2	3	1	6/5
I-1, I-7	5	4	1			5/4
I-1, I-7	16			3, 7, 11, 15	4	4/3
I-1, I-3, I-9	5	2, 4	2			7/5
I-1, I-3, I-9	16	0, 2, 4, 6, 8, 10, 12, 14	8			3/2
I-1, I-2, I-9	5	0, 1, 3	3			8/5
I-1, I-6	5				2	5/3
I-1, I-4, I-9	5	0, 1, 2, 3	4	1, 3		9/5
I-1, I-4, I-9	16	0, 1, 2, 3, 5, 6, 7, 8, 9, 10, 11, 13, 14, 15	14			15/8
I-6	16			1, 3, 5, 7, 9, 11, 13, 15	8	2

FIG. 6 is a block diagram having two MOs shown in FIG. 5(a). The output of the MI is connected to the two MOs in parallel.

FIG. 7 is a principal circuit diagram showing an overall electronic arrangement of the musical instrument according to the present invention. The frequency of pulse generator G will be modulated. A circuit N-1 actuates a pulse to be absorbed. The voltage of the lines connected to keyboard K is at a low level when the keys are not touched and, at a high level when the keys are touched. Pulse trains of a pulse period which are in proportion to the ratio of the fractionary number connected to the line, are consequently obtained when the line is in a high-volt condition. The pulse trains are passed to a cycle counter C-4 when an input line I-11 is in a low-volt condition.

After 240 total input pulses, the counter C-4 will return to the reset condition and the waveforms obtained are altered, filtered and widened into ideal forms by OUT-1. The wave forms are then converted into sound. The pulses which are being counted with the 240 total input pulses, are thus 240 times longer than that of the average pulse period of the pulse trains in which a pulse is absorbed. As shown in Table 1, the average pulse period of the pulse trains produced when the keys are touched is in proportion to the cycle per second of the sounds of the scales. Thus it should be noted that touching of the keys makes the pure temperament sounds of the musical scales (do-sharp has a slightly different ratio of the sound). If twelve keys are further provided and one of the keys are touched, the output pulse trains from the circuit N-1 pass through a flip flop F-7 and the average pulse period becomes twice as long when the input line which is connected to the key touched of the lines connected to the circuit N-1, and the input line I-11 are both in high-volt conditions. Thus the counter C-4 actuates completely every time 480 total output pulses and the sound of a one-line lowered octave can be obtained from OUT-1. If additional flip flops are used, sounds of more lowered lines of the octave can be obtained.

Modulations of the cycle per second of pulses produced by the pulse generator G corresponds to the modulation of the cycle per second of sounds produced from OUT-1. This modulation does not affect the ratios of the cycle per second of sounds. Thus, one can play in any keys or tones by modulating the frequency of the pulse generator G.

As illustrated in FIG. 7, the electric waveform obtained after 240 input pulses has exactly the same ratio irrespective of a touched key if the pulse generator G provides the same pulse period of the pulse trains. If for example, the counter actuates completely after 256 input pulses, the electric waveform thus obtained will not have exactly the same ratio. However, we can hear the thus obtained sounds as the same sound of which cycle has the average 256 input pulses.

The more numbers of pulses the cycle counter C-4 requires, the fewer the difference of period of the counter will take for one complete cycle. The average period the counter takes from a reset condition to the next reset condition will be referred to as cycle.

FIG. 8 is a block diagram showing a preferred form of the connections of the keys of the keyboards with the circuit N-1. Sounds of major keys are obtained when switches S-1, S-2, . . . to S-6 are connected with the lines as shown in FIG. 8. Sounds of minor keys are

obtained when switches S-1 to S-6 are connected with the opposite side of the lines of the above. The chromatic keys of keyboards produce half higher sounds than the keys positioned in the left sides. In this case, the chromatic keys of keyboards should be placed all between the keys for common tones and consequently the keys for use in the key-note are difficult to distinguish. Thus the keys of the above key-note or the keys for use in notes do, mi and sol are so colored or constructed of other shapes as shown in the Figure to solve the aforementioned problem.

FIG. 9 is a block diagram having a pulse generator G-0 of which frequencies are not modulated. Average pulse periods provided to the circuit N-1 are modulated by the circuit N-4. For instance, when a key G of a keyboard K-3 (—having key or tone names A to G—) is touched, the pulse trains from the pulse generator G-0 are provided to the circuit N-1 as an input-voltage. If key C of the keyboard is touched, the pulse trains of a 3 second longer average pulse period are provided to the circuit N-1. On the other hand, about sixteen fifteenth (and/or 135/128) average pulse period is provided in case that switches S-7 to S-13 are set to the left lines, and approximately fifteen sixteenth (and/or 25/24) average pulse period may be provided if switches S-7 to S-13 are set to the right lines. Thus, keys or tones in the A- to range are obtained when the switches are turned to the left, and keys or tones in the A- to G-sharp range are obtained when the switches are turned to the right.

In this method as illustrated in FIG. 9, frequencies of the pulse generator G-0 are settled and not to be modulated. Crystallized quartz may be used to stabilize the frequencies of the pulse period so that the correct sounds in any keys or tones can be obtained without any difficult tuning.

FIG. 9a shows another preferred form of a circuit in which pulse trains for making the musical scales of pure temperament can be produced. The circuit N-4 which sets a key or tone is connected together with the circuits N-1-I, N-1-II and N-1-III which set the musical scales. MOs, connected to each of these circuits can be used in stepping down the produce frequencies. Table 3 shows the combinations of the input of MOs and the input of MIs for producing the sounds of pure temperament.

Table 3

	Ratio of increase of average pulse periods by MO	Ratio of increase of average pulse periods by MI	Ratio of increase of average pulse periods by MO and MI (The products of MO and MI)
55	1	1	1
	16/15	1	16/15
	1	9/8	9/8
	16/15	9/8	6/5
	1	5/4	5/4
	16/15	5/4	4/3
	1	45/32	45/32
60		3/2	3/2
	8/5	1	8/5
	4/3	5/4	4/3
	8/5	9/8	9/5
	1	15/8	15/8
	4/3	3/2	2

If, for example frequency of the pulse generator G-0 is 608 KHz or 1216 KHz, the key G is produced when any pulse of the above is not absorbed. The note sol of

the highest line of the octave can be obtained if none of the 256 total input pulses are absorbed. The sound produced by pianos. Various kinds of modification are possible, for example, the frequency of the pulse generator G-0 should be lower than the above if a bass musical instrument is desired. It is also possible that the frequency can be higher than the above mentioned frequency and that more numbers of total input pulses for the cycle can be provided to obtain a variety of tone quality and sounds.

In the musical instrument having a preferred form of the circuit as illustrated in FIG. 7 or FIG. 8, a key or tone is determined by the cycle per second or average pulse period of the pulses supplied from the pulse generator G. This would facilitate the playing of the instrument since the sound of the same scale can be produced in any keys or tones by using same keys of keyboards.

Various advantages of the electronic musical instrument according to the present invention will become apparent by applying the principles of the invention.

One of the advantages is to make various kinds of waveforms with the output of the cycle counter.

FIG. 10 shows a preferred form of the above-mentioned circuit. If the cycle counter C-4 is composed of a binary systemized counter, the indicated numbers of five bits counted from the number positioned at the top flow into the output portions OUT-2 and are converted into a code of the numbers of six bits in binary form by a code converter CC. The code then converted into a proportional analog voltage by a digital-analog converter D-A. Thus, staircase waveforms having 32 stairsteps per cycle are produced. Since the height of each stairstep is determined by the code of the code converter CC, arbitrary 32 waveforms per cycle can be produced.

If more numbers of stairsteps per cycle are required, more numbers of bits coming from the cycle counter C-4 should be supplied. If more ideal height of each stairstep is required, more numbers of bits converted by the code converter CC should be produced. OX of the OUT-2, shown in FIG. 10, is a circuit in which amplifying of the pulse-width, filtering of the waveforms and conversion into sounds occurs.

FIG. 11 illustrates another preferred form of a circuit in which arbitrary waveforms are produced by the output of the cycle counters. A counter C-5 is connected in cascade with a reversible counter RC-1 and the indicated numbers of the reversible counter are converted into an analog voltage.

The output from the reversible counter RC-1 is fed to a digital-analog converter D-A-Z which produces staircase waveforms having 64 steps. The staircase waveforms are then filtered and converted into sawtooth waveforms by a filter FL. Cycles of the sawtooth waveforms correspond to the ratio of an average input pulse period to the cycle counter C-5 and the amplitude of the sawtooth waveforms are not modulated in any musical scale. The sawtooth waveforms pass through a nonlinear circuit NL which modulates the waveforms.

FIG. 12 illustrates the produced waveforms by the nonlinear circuit NL.

FIG. 13(a) is a schematic circuit diagram having the cycle counter C-4 as well as another counter C-6 in which an indicated number changes more slowly than that of the counter C-4. The output of a comparator

5 COM keeps the circuit in a high-voltage condition while the indicated numbers of the counter C-4 are larger than the numbers of the counter C-6. The output of the comparator COM becomes a low-volt condition when the indicated numbers of the counter C-4 are smaller than the numbers of the counter C-6. Thus, the output of the comparator COM-1 becomes shorter as the indicated number of the counter C-6 become larger. This produces the waveforms illustrated in FIG. 10 13(b).

10 The waveforms are filtered by a low pass filter and converted into sounds. The wider waveforms are converted into louder sounds and the narrow waveforms into softer sounds.

15 As shown in FIG. 13a, the input of counter C-6 is connected to the output of a third counter C-10. The input of this counter C-10 is connected to the output of the comparator COM-1 and the input of the cycle counter C-4. The comparator COM-1 compares the outputs of counters C-4 and C-6.

20 Various kinds of sounds can be produced by changing the periods of pulses which are supplied to the counter C-6. The counter C-6 is reset when a key of the keyboards is touched.

25 FIG. 13(c) is a block diagram in which the code converter CC and the digital-analog converter DA-1, shown in FIG. 11, produce arbitrary waveforms. The voltage produced by the digital-analog converter DA-2 corresponds to the ratio of the complement of the indicated numbers of the counter C-6. The waveforms produced by the digital-analog converter DA-1 are modulated by the this obtained voltage. Modulation of the above is made by the known technology.

30 As shown in FIG. 13c, the input of the modulator MOD is connected to the outputs of two digital-analog converters DA-1, DA-2. The output of this modulator is connected to an analog-sound converter OX.

35 FIG. 14 is a schematic circuit for producing a continuous glide effect of sounds, such as portamento, the pulse trains of an input line I-13 become the input of cycle counter C-4 when the indicated numbers of the counter C-7 are smaller than indicated numbers of last six bits of the counter C-4. The pulse trains of an input line I-14 become the input of the counter C-4 when the indicated numbers of the counter C-7 is equivalent to or larger than the numbers of the last six bits of the counter C-4. The pulse trains of both the input lines I-13 and I-14 work in many shifts per cycle of a sound. Thus the cycle counter C-4 has returned to the reset condition after 256 total input pulses which are supplied from the input lines I-13 and I-14.

40 45 50 55 60 65 FIG. 15 is a schematic circuit diagram showing a preferred form of a circuit for periodic variations in the pitch of sounds, such as vibrato. Indicated numbers of the reversible counter RC-2 increase every time a pulse is supplied to the input line I-16 and the input line I-15 is in a high-volt condition. When its reversible counter RC-2 reaches the maximum, the increase stops because the output of an exclusive OR circuit E-11 changes to a low-volt condition. Indicated numbers of the reversible counter RC-2 decrease one by one when the input line I-15 is in a low-volt condition, and the decrease stops when the indicated numbers of the reversible counter RC-2 reaches the minimum. Thirty one pulse are required for the cycle actuation of the counter C-1 when the indicated numbers of the reversible counter RC-2 are larger than the indicated numbers of the

counter C-9. Counter C-8 returns to its cycle actuation after thirty two pulses when the indicated numbers of the reversible counter RC-2 are smaller than or are equivalent to the indicated numbers of the counter C-9. Thus, the number of input pulses required for the cycle actuation of the cycle counter C-4 are subtracted by the indicated number or numbers of the reversible counter RC-2, and the sounds thus produced are high-pitched. As illustrated in FIG. 15, the counter C-4 has returned to the reset condition after 248 total input pulses (which are the fewest numbers of the pulses in this case), and the sound produced is one quarter of a step higher under the condition that the frequencies vary unsuccessfully in eight steps. Effectiveness of the periodic variations in the pitch of tones, such as vibrato, can be produced by changing the conditions of the input line I-15 at a high voltage or at a low voltage by means of the cycle of vibrato automatically, or by hand.

By producing slightly different pitch sounds, FIGS. 15(a) and 15(b) produce a sound having a depth and/or express mixed feelings. As shown in FIG. 15(a), if the pulse trains required for the cycle counters C-4 and C-5 to return to the reset conditions are slightly different in number, the sounds produced from the counter C-4 and that from the counter C-5 will have a slightly different pitch. The cycle counter C-4 returns to the reset condition after 256 pulses and the cycle counter C-5 returns to the reset condition after 259 pulses. Consequently the sounds produced from the counter C-4 and that from the counter C-5 have a slightly different pitch corresponding to the ratio of 256 to 259. FIG. 15(b) is a schematic circuit diagram showing another preferred form of a circuit in which slightly different sounds in pitch can be produced. An inhibit gate circuit A-38 is connected with the cycle counter C-5 which returns to the reset condition after the same total input pulses as the cycle counter C-4 does. Thus, a pulse of 60 pulses or a pulse of 120 which are provided to the inhibit gate circuit A-38 is prevented to pass.

Two different sounds are in harmony if the two sounds are in scales of pure temperament and their periodic vibrations are in simply proportional each other. But in FIG. 7, only one sound is produced if two keys of the keyboard are touched at the same time. Therefore, the circuit as shown in FIG. 7 is not a preferred form with regard to the above and, the circuit shown in FIG. 16 covers the disadvantage of the circuit in FIG. 7.

Reference is now made to FIG. 16 which illustrates a circuit arrangement having selective circuits between a keyboard K-4 and the circuits N-1 to N-3. When more than one key of the keyboard K-4 are touched at the same time, one signal from a key of the keyboard K-4 is provided to the circuit N-1, another signal from another key to the circuit N-2, the other signal from the other key to the circuit N-3. In order to be brief, the arrangement of the Figure has eight keys of the keyboard K-4 as well as the circuit N-1 to N-3.

In the above drawing, the same signs of the same numerals are marked with a double circle to show that they are connected to each other. Inhibit gate circuits A-15 to A-38 which are connected with the keys and with the circuit N-1 to N-3 actuate to pass a signal when no signal input is supplied in a high-volt condition. For example, the inhibit gate circuits A-15, A-23 and A-31 are communicated each other via a key.

When a signal from the key passes through the inhibit gate A-15, other signals from the key are prevented to pass through both inhibit gates A-23 and A-31. There are three groups in the Figure: Group I includes the circuits A-15 to A-22; Group II includes the circuits A-23 to A-30 and Group III the circuits A-31 to A-38. In this arrangement, if a key is touched, the signal of the key is provided to the circuit N-1 passing through one of the inhibit gate circuit in the Group I and the signal does not pass through the gates of the Group II or III.

If another key is touched at the same time the first key is being pressed, the signal from this second key is provided to the circuit N-2 passing through the gate of the group II. In this way, the circuits N-1, N-2 and N-3 actuate to produce sounds corresponding to keys which are depressed at the same time. The keyboard K-4 has eight keys and only three sounds can be produced at a time in the circuit shown in FIG. 16. However, it is apparent that more variety of sounds in pitch can be produced at by equipping more numbers of keys of keyboards and, more numbers of sounds can be produced simultaneously by arranging more numbers of the gate groups and the circuits such as N-1 to N-3 of the above.

FIG. 17 is a schematic circuit diagram having another preferred form of a circuit in which a keyboard K-2 is used for sounding the notes of the scales of a main melody. The output pulse trains of which average pulse periods correspond to a touching key of the keyboard K-2, are produced from a circuit N-1. A keyboard K-5 is so arranged that two lowered sounds in pitch than the sounds from the keyboard K-2 can be produced simultaneously with the sounds from the keyboard K-2. One of the output pulses is pulled out by a circuit N-4 by touching a key of the keyboard K-5. Average pulse periods of the output pulses from the circuit N-4 are six-fifth times or five-fourth times as long as average pulse periods of the output pulses from the circuit N-1.

When the touching keys of the keyboard K-2 are mi in major, la in major and ti in major respectively, average pulse periods of the output produced by the circuit N-4 are five-fourth times respectively as long as the average pulse periods of each of the notes of the above circuit N-1 by touching the keys of the keyboard K-5. In this case, average pulse periods of other notes of the above circuit are six-fifth times as long respectively.

A keyboard K-6 is so arranged that five lowered sounds in pitch than the sounds from the keyboard K-2 can be produced simultaneously with the sounds from the keyboard K-2. The output pulse trains of which average pulse periods are five/third times or eight/fifth times as long as that from the circuit N-1, are produced from the circuit N-5. When touching keys of the keyboard K-2 are re, mi, la in major and si in major, average pulse periods of the output produced by the circuit N-5 are five/third times as long as the average pulse periods of each notes of these in the circuit N-1. Average pulse periods of other notes above-described are eight/fifth times as long respectively.

Three sounds which are different from each other in pitch are produced from the output pulse trains of the circuit N-1, N-4 and N-5. Periodic vibrations of the three sounds are in proportion to the average pulse periods of the circuit N-1, N-4 and N-5 respectively.

These three sounds can be produced by providing the three cycle counters with the output pulse trains from the circuit N-1, N-4 and N-5. They may return to a reset condition after the same total input pulses in num-

ber. Thus, the sounds in harmony with a main melody can be produced at by the process described above. These sounds are more in harmony with the melody than the sounds which are obtained by striking the same notes of the scales of equal temperament arranged in the common keyboard musical instrument. It is apparent that the sounds produced in the process above described are not limited to two or five lowered sounds in pitch, but is covers any of different sounds in pitch.

FIG. 18 is a schematic circuit diagram showing a preferred form of a circuit in which three chords can be produced. The frequencies of the pulse generator G-0 are settled and not to be modulated. As shown in FIG. 9, the circuit N-4 is used for pulling out a pulse to determine the keys or tones. It is connected with the input lines and actuates when one of the input lines is in a high-volt condition.

The output pulse trains of the circuit N-4 are pulled out by circuits N-1, N-6 and N-7 and become three kinds of pulse trains with different pulse periods. D-1

5

10

15

20

D-1, the average pulse periods are twice the number of what they are. The output does not step down by the circuit D-2 in this case. Thus, the average pulse periods of the output pulse trains from the OR gate circuits OR-6 and OR-7, and the circuit N-7 become three times, twice and twelve/fifth times respectively as long as what they are and, are converted into sounds by counting the same numbers by the counters. The sounds produced are, if the sound converted from the

output of the circuit N-4 is settled to be the note sol, one-line lowered do in octave, one-line lowered sol in octave and one-line lowered mi in octave. The three chords composed of the notes do, mi and sol can be thus produced.

Table 4 shows the ratios of increases of the pulse periods at the output voltage in the three circuit for pulling out a pulse and in the two circuit for stepping down of the frequencies. It also shows the syllable names produced in the process as mentioned above. (The sound converted from the output, of which pulse does not being pulled out, provided by the circuit N-4 is settled to be the note sol.)

Table 4

Ratio of increase of average pulse periods provided by N-1	"					Output pulse periods of OR-6, OR-7 and N-7	Ratio of pulse periods and arranged in order from longer one of the left column	Syllable names			
	by N-6	by N-7	by D-1	by D-2							
3/2	4/3	8/5	2	1	3	2	12/5	3/2 : 6/5 : 1	do	mi in major	sol
9/8	4/3	8/5	2	2	9/4	3	8/5	3/2 : 9/8 : 4/5	do	fa	la in major
1	4/3	8/5	1	1	1	4/3	8/5	8/5 : 4/3 : 1	si in major	re	sol

45

is a circuit used in the step-down of frequencies. When an input line I-17 is in a low level condition, the output of the circuit D-1 is in the same average periods as the output of the circuit N-1. When the input line I-17 is in a high level condition, a flip flop F-8 steps down the frequencies of the output voltage of the circuit N-1 and the pulse trains, which are twice as long in average period, can be produced by the circuit D-1. A circuit D-2 has the same arrangement as the circuit D-1. When the output voltage does not step down by the circuits D-1 or D-2, the periodic vibrations of the sounds produced by counting the outputs from the circuits D-1, D-2 and N-7 by the three counters are in proportion to the average periodic vibrations of the output pulse trains from the circuits N-1, N-6 and N-7.

When the numbers of pulses are decreased by the circuit D-1 or by both the circuits D-1 and D-2, inverted chords can be produced. When a key K-7 is touched, each average pulse period of the circuits N-1, N-6 and N-7 become three/second times four/third times and eight/fifth times, respectively what they were if that key K-7 was not pressed. Being stepped down by the circuit

50

65

Three kinds of pulse trains are supplied to the three counters respectively. This enables the electronic musical instrument to produce not only the chords above described but also to produce the broken chords by providing the counters with the pulse trains periodically in order.

The three chords that are described and shown in Table 4 are limited only to the familiar three chords, yet it is apparent that various kinds of triads and the chords of four or more tones are able to produce by the same method as described above.

It is apparent that the electronic musical instrument according to the present invention has the advantage of being easy for a player to play since touching a key on the keyboard produces the corresponding note of the key on the keyboard irrespective of any keys or tones. The sounds of the musical scales of pure temperament can be produced correctly in any keys or tones, various kinds of tones in pitch and of chords that are difficult to produce in the pure temperament are easily able to produced. Harmonized in depth sounds can be easily produced and it is possible to play the instrument by

determining sounds in pitch and sounds of waveforms arbitrarily. The advantages mentioned above enable an untrained player, fond of music, to learn how to play the instrument quickly and accurately.

What is claimed is:

1. An electronic musical instrument having a circuit means comprising:

a pulse train generating means producing a pulse train having variable periodic or average pulse periods;

a first keyboard having a plurality of keys corresponding to the notes of do, re, mi, fa, sol, la, and ti;

a second keyboard having a plurality of keys corresponding to the keys A, B, C, D, E, F and G;

a first circuit arrangement connected to said first keyboard for absorbing or pulling out a pulse of said pulse train in response to the depression of a key of said first keyboard;

a second circuit arrangement connected to said second keyboard, for modulating the periodic vibrations or average pulse periods of said pulse train in response to the depression of a key of said second keyboard;

cycle counter means for producing a waveform, including a first cycle counter for counting the pulses absorbed or pulled out by said first circuit arrangement, and for returning to reset after a predetermined number of input pulses have been counted; and

output means connected to said cycle counter means for amplifying and converting waveform into sound, said output means including code converter means for converting the counted number of pulses counted by said cycle counter, into codes, a first digital-analog converter means for converting said codes into analog voltage and analog-sound converter means for converting said analog voltage into sounds.

2. An electronic musical instrument according to claim 1 wherein said first circuit arrangement absorbs or pulls out pulses of a pulse train modulated by said second circuit arrangement.

3. The electronic musical instrument according to claim 1, wherein said first circuit arrangement absorbs or pulls out said average pulse periods in proportion to 1, 8/9, 5/6, 4/5, 3/4, 2/3, 5/8, 3/5, 5/9 and 8/15 for each individual note or of second, fourth, eighth and so on powers of two and, wherein both major and minor keys having the same key-note can be produced.

4. The electronic musical instrument according to claim 1, wherein said cycle counter means further includes a second counter and a third counter for advancing a single count upon the passage of a predetermined number greater than one of pulses, and a comparator for comparing the counts registered on said cycle counter and said second counter and producing a high voltage-low voltage digital waveform therefrom by changing a high voltage condition to a low voltage condition dependent upon the relative magnitude of the counts, the input of said third counter connected to the output of said comparator and the input of said cycle counter, and the output of said third counter connected to said second counter.

5. The electronic musical instrument according to claim 4, wherein said output means comprises a second digital-analog converter means for converting said high

voltage-low voltage digital waveforms into analog voltage, a modulator means, the input of which is connected to the outputs of said first and second digital-analog converter means and the output of said modulator means is connected to said analog-sound converter means, for modulating said voltage.

6. The electronic musical instrument according to claim 1 also comprising:

a third keyboard having a plurality of keys corresponding to lowered steps of the notes of said first keyboard; and

a third circuit arrangement connected to said third keyboard for absorbing or pulling out pulses of a pulse train absorbed or pulled out by said first circuit arrangement in response to the depression of a key of said third keyboard.

7. The electronic musical instrument according to claim 1 also comprising:

a fourth keyboard having a plurality of keys corresponding to the chords of the notes of said first keyboard; and

a fourth circuit arrangement connected to said fourth keyboard for absorbing or pulling out pulses of a pulse train absorbed or pulled out by said first circuit arrangement in response to the depression of a key of said fourth keyboard.

8. The electronic musical instrument according to claim 7, wherein, when an average pulse period of the output pulse trains from said pulse generating means is designated as 1, the pulse trains of three kinds of average pulse periods selected from the average pulse periods are produced in proportion to 1, 9/8 or 3/2 for the first, 8/7 or 4/3 for the second, and 8/5 or 5/3 for the third said pulse train.

9. The electronic musical instrument according to claim 1 wherein said first circuit arrangement comprises a plurality of circuits and selective circuits equipped between said circuits and said first keyboards for supplying the signal produced from touching a key to one of the plurality of circuits, for preventing said signal from being supplied to other of said plurality of circuits for ensuring that a circuit provided with a signal from touching one key of said first keyboard will not accept other signals from touching another key of said keyboard.

10. An electronic musical instrument having a circuit means comprising:

a pulse train generating means producing a pulse train having variable periodic or average pulse periods;

a first keyboard having a plurality of keys corresponding to the notes of do, re, mi, fa, sol, la, and ti;

a second keyboard having a plurality of keys corresponding to the keys A, B, C, D, E, F and G;

a first circuit arrangement connected to said first keyboard for absorbing or pulling out a pulse of said pulse train in response to the depression of a key of said first keyboard;

a second circuit arrangement connected to said second keyboard, for modulating the periodic vibrations or average pulse periods of said pulse train in response to the depression of a key of said second keyboard;

cycle counter means for producing a waveform including a cycle counter for counting the pulses ab-

sorbed or pulled out by said first circuit arrangement, and for returning to reset after a predetermined number of input pulses have been counted, said cycle counter means further including a reversible counter means for incrementally increasing from a preselected minimum number until a maximum number is reached, said cycle counter being connected in cascade with said reversible counter means; and
